DESIGN FOR A TEXTILE FABRIC

Henry Allen Schubart, Ossining, N. Y.

Application April 14, 1938, Serial No. 76,493
Term of patent 3½ years

To all whom it may concern:

Be it known that I, Henry Allen Schubart, a citizen of the United States, residing at Ossining, in the county of Westchester and State of New York, have invented a new, original, and ornamental Design for a Textile Fabric, of which the following is a specification, reference being had to the accompanying drawing, forming part thereof.

The figure is a plan view of the textile fabric showing my new design.

The design comprises a series of self color twill crosses arranged on a plain background, as shown.

I claim:

The ornamental design for a textile fabric, substantially as shown and described.

HENRY ALLEN SCHUBART.
